UNITED STATES PATENT OFFICE

WILLIAM M. SHEEHAN, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

CAB UNDERFRAME

Application filed February 15, 1929. Serial No. 340,197.

My invention relates to railway rolling stock and consists in a novel underframe structure for use in railway vehicles and in the assembly of certain superstructure elements therewith. I illustrate my invention as applied to oil-electric locomotives but its use is not limited to such embodiment. It has been the practice to mount the oil engines on top of the underframe and one of the objects 5 of my invention is to form the engine sub-bases as a part of the underframe and located below the top thereof thereby decreasing the total depth from the center line of the engine crank shaft to the bottom of the underframe. 10 This lowers the center of gravity of the locomotive and reduces the total weight of a structure employing a separately formed sub-base.

Another object of my invention is to form 15 in the underframe a compartment below an engine crank shaft to receive lubricating oil and having a removable oil sump. I also desire to provide the above mentioned compartment with suitable openings and closures therefor whereby the lower connecting rod 20 bearings may be inspected.

Another object of my invention is to provide a box shaped center or draft sill to form 25 a more rigid structure and to combine therewith intermediate sills and side sills serving as supports for the upper portions of engines and for generators. Associated objects are to obtain a minimum weight and maximum 30 rigidity in a given structure so as to withstand the vibrations of the engine and weaving of the underframe as a result of vertical track reactions or longitudinal buffing and pulling forces which otherwise would result 35 in disalignment of engine crank shaft bearings and generator shaft bearings.

Another object of my invention is to form 40 an engine crank shaft bearing integrally with the sub-base.

Another object of my invention is to locate 45 fuel oil reservoirs or other liquid compartments in the underframe and preferably to form these reservoirs integrally with the underframe structure. In a locomotive having a 50 plurality of engines disposed on opposite sides of the longitudinal center line of the

vehicle, it is desirable to locate these liquid compartments on opposite sides of the vehicle also and it is another object of my invention to connect these compartments with suitable passageways so that the liquid level therein may be maintained constant to maintain an even weight of liquid on each side of the underframe. 55

Another object of my invention is to provide in the underframe structure suitable 60 space for locating the water circulating pipes so that the same may be run entirely around the underframe.

Another object of my invention is to provide 65 an underframe having different levels for supporting the engines and generators and for supporting the operator's compartment and, at the same time, to provide for a substantially horizontal lower edge of the 70 superstructure side wall applied to the underframe. 75

The above and various other detailed objects of my invention are attained by the 75 structure illustrated in the accompanying drawings in which—

Figure 1 is a top view of the underframe with some piping attached thereto.

Figure 2 is a vertical section taken on the longitudinal center line of the underframe. 80

Figure 3 is a side elevation of the same.

Figure 4 is an end view of the underframe.

Figures 5, 6, 7 and 10 are vertical transverse sections taken on the lines 5—5, 6—6, 7—7 and 10—10 of Figure 1. 85

Figures 8 and 9 are vertical longitudinal sections taken on the lines 8—8 and 9—9 of Figure 1.

Preferably, the underframe is an integral 90 structure formed by casting or welding and such construction makes it possible to obtain many of the objects set forth above far more effectively than would be possible with a built-up structure. The main longitudinal member of the underframe is a center sill of box shaped section comprising vertical sides 1 and horizontal top and bottom walls 2 and 3, respectively, which are provided with 95 openings to lighten the structure and to provide access to piping and other equipment 100

which may be located within the center sill. Intermediate sills 4 and side sills 5 parallel the center sill 1—2—3 and the bolsters 6, and end sills 7 connect the longitudinal sill members and are formed integrally therewith. Transverse braces 27 connect the intermediate and side sills at intervals.

Each side wall 1 of the center sill forms one side of the sub-base of an oil engine and 10 the corresponding portion of the adjacent intermediate sill 4 forms the other side of the engine sub-base. These sub-base forming portions of the sills are provided with integral transverse webs 8 (Figure 8) which 15 reinforce the structure and also mount the crank shaft bearings 9. Additional transverse reinforcing elements are shown at 10 below webs 8. The intermediate sills 4 are of greater depth adjacent the engine structure, as best shown in Figure 3, and at these 20 portions are provided with openings 11 through which the lower crank shaft bearings may be inspected. These openings will be surrounded by suitable pads 12 which may 25 be finished to receive removable cover plates 13. At least one plate will have a filling spout 40.

Beneath each engine is provided a detachable structure 14 which forms an oil pan 15 immediately below the sills and also includes a compartment 16 for the lubricant supply.

Between one end of each sub-base and the adjacent bolster, the center sill and one intermediate sill 4 is modified as shown at 17 in Figure 7 to accommodate the lower portion of the generator G; this structure being duplicated at diagonally opposite portions of the inter-bolster portion of the underframe.

On the opposite sides of the bolsters from element 17, I provide fuel reservoirs or compartments 18, the side walls of which are formed by the center and intermediate sill 45 webs, and the compartment top and bottom walls 19 and 20, respectively, serve to form, with the side wall, a box shaped structure which is closed at its ends by one of the bolster webs 21 and by a suitable additional 50 transverse web 22. A by-pass 23 connects the compartments on opposite sides of the longitudinal center line and extends through the center sill. Another by-pass 24 extends from one pair of compartments through the 55 bolster and is provided with a fitting whereby the compartments at the opposite ends of the underframe may be connected with each other by suitable piping 25 which leads to the fuel oil sump 26 located at a lower level 60 than the tanks and from which the fuel may be pumped to the engines. The top walls of the reservoirs are provided with cored 65 openings 41 to suit molding conditions and for cleaning out the core sand, which openings are closed by the plates 42 welded on

as shown at W. The fuel oil inlet and vent is shown at 43. The openings and plates can be provided in either the top or bottom wall.

Bolsters 6 and braces 27 have suitable 70 openings 28 in substantial alignment longitudinally of the underframe and these openings are approximately the same level as openings 29 provided in the center sills and intermediate sills just inside of the end sills. 75 The water circulating pipes (not shown) for cooling the engines and for train lines extend through these openings 28 and 29 entirely around the underframe and I believe it is broadly new construction to provide an unobstructed path for such piping adjacent to the sides and ends of a locomotive underframe.

The truck motors (not shown) are air 80 cooled from an air current generated within the engine room. An air blower 44 is located substantially over each truck center plate C and a conduit 30, (Figure 5) is formed in each bolster above the truck center plate and the walls of this conduit also serve as 85 bolster elements. This and similar structure is detailed and described in my co-pending application Serial Number 299,331, filed August 13, 1928, now Patent No. 1,766,406 of June 24, 1930.

The lower portion of the cab side and end sheets 31 are secured to the underframe by angles 32 mounted on suitable pads 33 on top of the underframe, the bottom edges of the sheets projecting below the angles 32 and contacting with the outer edges of pads 33. The top of the intermediate portion of each side sill is on a higher level than the top of the end portions of the sill and, at this higher portion, the superstructure side sheets are fastened to a finished pad 34 which is spaced a substantial distance from the top of the sill and is somewhat wider than the outer edges of pads 33. This provides for a continuous lower support for the side sheets extending in a horizontal line from end to end of the underframe.

The side sheets intermediate the end portions are braced by means of vertically disposed channels 35 which are turned inwardly at their lower ends and secured to the top of the side sill.

The cab floor 36 is carried on angles 37 secured to the side sheets and to inner partitions 38 or the floor may be mounted upon stringers (not shown) carried on the underframe structure.

Obviously, the method of attaching the side sheets may be varied substantially so different structural elements may be used and the parts riveted or welded together in many different ways.

It is obvious that in a structure of the size and complications described above, many parts may be modified or eliminated with- 130

out affecting the integrity of the remaining structure. Many of the parts which are shown as formed integrally with the main underframe could be formed separately therefrom and attached thereto. Also, many parts shown separate could be formed integral without departing from the spirit of my invention. The liquid compartments have been shown on this locomotive as located beyond the bolster, but their location at other places within the cab underframe are considered as coming within the spirit of this invention. Also, connecting elements can be modified to suit the different locations.

It will be understood that my invention is not limited to the complete combination of all of the elements shown and I contemplate the exclusive use of such variations in the 20 described structure as come within the scope of my claims.

I claim:

1. In a railway vehicle, an underframe including an engine sub-base, a cab carried on 25 said underframe, and a liquid compartment located between said sub-base and the end of said underframe and below said cab.

2. In a railway vehicle, an underframe including an engine sub-base, a cab carried on 30 said underframe, and a liquid compartment located between said sub-base and the end of said underframe and below said cab and formed integrally with said underframe.

3. In a railway vehicle underframe, elements for mounting an engine, members for supporting a cab floor, and a liquid compartment formed in said underframe between 35 said elements and the end of said underframe and below said members.

4. In a railway vehicle underframe integral structure, elements for mounting an engine, members for supporting a cab floor, and a liquid compartment formed in said structure between said elements and the end of said underframe and below said elements and members.

5. In a railway vehicle underframe, cab floor supporting members, and a plurality of liquid compartments formed in said underframe and below the top of said members and in balanced relation on opposite sides of 50 the longitudinal center line of said locomotive.

6. In a railway vehicle underframe, cab floor supporting members, and a plurality of liquid compartments formed in said underframe and below the top of said members and in balanced relation on opposite sides of the longitudinal and transverse center lines of 55 said locomotive.

7. In a railway vehicle underframe structure, a plurality of separated liquid compartments each comprising a complete closed tank, said compartments being formed in 60 said structure and arranged in balanced rela-

tion on opposite sides of the longitudinal center line of the structure.

8. In a railway vehicle underframe, a center sill, a longitudinal sill spaced therefrom, and a bolster connecting said sills, said sills and bolster forming three side walls of a liquid compartment, and other elements forming a fourth side wall and top and bottom walls of said compartment.

9. In combination, a railway vehicle underframe casting, a liquid compartment having side walls and substantially horizontally top and bottom walls integral with the casting, there being an opening in at least one of said horizontal walls, and a separately formed plate secured to said casting for closing said opening.

10. In a railway vehicle, an underframe having a center sill member, a bolster member, an end sill, and a longitudinal sill member spaced from said center sill member, a cab floor, a liquid compartment formed integral with said casting below said floor, said compartment being located in the space between said bolster and end sill and between 90 said center sill member and said longitudinal sill member, said members having vertical webs comprising side walls of said compartment.

11. In a railway vehicle, an underframe having a center sill member, an end sill member, a bolster member, and a longitudinal sill member spaced from said center sill member, a cab floor, a compartment adapted to contain liquid and formed integrally with said casting and located below said floor in the space between said members on one side of said underframe, another compartment adapted to contain liquids located on the opposite side of said underframe, said compartments being arranged substantially symmetrical with respect to the longitudinal center line of said casting.

12. In a railway vehicle integral underframe structure, a center sill, separated liquid compartments spaced apart on opposite sides of said sill each comprising a complete closed tank, and a conduit extending between said compartments through said sill.

13. In a locomotive integral underframe structure, liquid compartments spaced from each other on opposite sides of the center line of the structure, and a passageway connecting said compartments.

14. In a railway vehicle underframe, sill members, liquid compartments integral with said sill members and located below the top of the underframe, and a by-pass integral with and connecting said compartments.

15. In a railway vehicle underframe, a bolster, a liquid compartment comprising a complete closed tank located at one side of said bolster, and a conduit integral with said bolster and extending from said compartment through said bolster.

16. In a railway vehicle underframe, a bolster, a liquid compartment at one side of said bolster and formed integrally therewith, and a conduit integral with said bolster and 5 compartment and extending through said bolster.
17. In a railway vehicle underframe, a bolster, a sill integral therewith, a liquid compartment at one side of said bolster and said 10 sill, and a conduit integral with said bolster and sill extending from said compartment through said bolster and sill.
18. In a railway vehicle underframe, a center sill, liquid compartments located on 15 opposite sides of said sill, said compartments being located equi-distant from the longitudinal center line of said underframe and the tops of said compartments being spaced below the top of said sill.
19. In a railway vehicle underframe, a center sill, liquid compartments located on opposite sides of said sill, said compartments being located equi-distant from the longitudinal center line of said underframe and the 25 tops of said compartments being spaced below the top of said sill, all of said elements being formed in a one-piece casting.
20. In a railway vehicle underframe integral structure, a center sill, bolsters, end sills, 30 liquid compartments in the spaces between said bolsters and end sills, on each side of said center sill, and engine sub-bases between said bolsters on each side of said center sill.
21. In a railway vehicle underframe integral structure, a center sill, bolsters, end sills, 35 liquid compartments in the spaces between said bolsters and end sills on each side of said center sill member, and engine crank cases between said bolsters and on each side of said 40 center sill.
22. In a railway vehicle underframe, the combination of a liquid compartment and an engine sub-base spaced therefrom and integral therewith.
23. In a railway vehicle underframe integral structure, the combination of a liquid compartment and an engine sub-base integral therewith, said compartment being located 45 below the top of said structure.
24. In a railway vehicle underframe integral structure, a center sill, longitudinal sills spaced from said center sill, said sills forming engine sub-bases on opposite sides of the longitudinal center line of the underframe.
25. A railway vehicle underframe having a center sill, longitudinal sills spaced from said center sill, said sills forming engine sub-bases on opposite sides of the longitudinal center line of the underframe, elements in said 50 sub-bases extending transversely thereof and providing crank shaft bearings, all of said parts being formed in an integral structure.
26. In a railway vehicle underframe, an integral structure having longitudinal sill 55 members forming an engine sub-base extend- ing substantially the full depth of said mem- bers and being open at the bottom, and a detachable member for closing the bottom opening in said structure. 70
27. In a railway vehicle underframe, an integral structure having longitudinal sill members forming an engine sub-base extending substantially the full depth of said members and being open at the bottom, there being transverse elements in said structure providing crank shaft bearings, and a detachable member for closing the bottom opening in said structure. 75
28. In a locomotive underframe integral structure, spaced longitudinal sill members having vertical webs, said webs forming the side walls of an engine sub-base, there being an opening in one of said walls for access to the interior of said sub-base, and a separate cover plate for closing said opening and secured to the latter. 80
29. In a locomotive underframe integral structure, spaced longitudinal sill members having vertical webs, said webs forming the side walls of an engine sub-base, said walls extending vertically to the bottom of the sub-base, and transverse members between said side walls having crank shaft bearings. 85 90
30. In a railway vehicle underframe integral structure, longitudinal sill members having vertical webs, portions of which webs comprise a support for a generator, said portions being inclined so as to provide clearance between them for the generator housing. 95
31. In a railway vehicle underframe integral structure, longitudinal sill members having webs disposed vertically for the greater portion of their length but inclined throughout opposed portions of their length so as to provide a wider space between them to clear 100 a generator housing mounted on said members. 105
32. In a railway vehicle underframe integral structure, longitudinal sill members having vertical webs, a portion of the tops of said sills being offset transversely to support a generator housing and the lower portions of said webs being inclined upwardly to clear the generator housing. 110
33. In a railway vehicle underframe integral structure, spaced longitudinal sill members the upper portions of which form supports for an engine and a generator, the portions forming supports for the generator being spaced apart a greater distance than the 115 portions forming a support for the engine. 120
34. In a railway vehicle underframe integral structure, spaced longitudinal sill members forming supports for an engine and a generator, said members being offset throughout a portion of their length to accommodate the variation in the widths of the engine and generator supported thereon. 125
35. In a railway vehicle underframe integral structure, three longitudinal sill mem- 130

bers, an engine sub-base formed integral with said structure between the center member and one of the other of said members, and another engine sub-base formed integral with said structure between the center member and the third of said members.

36. In a railway vehicle underframe integral structure, three longitudinal sill members, and an engine sub-base, having crank shaft bearings, formed integral with and located between the center and one of the other of said members, and another engine sub-base having crank shaft bearings and formed integral with and located between the center and the third of said members.

37. In a railway vehicle underframe integral structure, an engine sub-base extending longitudinally of the structure and between the longitudinal center line thereof and the side of the structure.

38. In a railway vehicle, an underframe, and an engine sub-base within the sides of said structure and extending longitudinally of said under-frame and spaced from the longitudinal center line thereof and constituting a structural element of said underframe.

39. In a railway vehicle underframe integral structure, an engine sub-base within the sides of said structure and arranged longitudinally thereof and spaced from the longitudinal center line thereof and including crank shaft bearings.

40. In a railway vehicle underframe, bolsters, and a plurality of engine sub-bases integral with and located between said bolsters.

41. In a railway vehicle underframe integral structure including bolsters and a plurality of engine sub-bases having crank shaft bearings, said sub-bases being integral with and located between said bolsters.

42. In a railway vehicle underframe integral structure comprising a box section center sill member, a longitudinal sill member on each side of said center sill member, a pair of engine sub-bases arranged longitudinally of said structure, said bases being arranged symmetrically with respect to the longitudinal and transverse center lines of said structure.

43. In a railway vehicle underframe integral structure, a center sill member and longitudinal sills on each side of said center sill member, a pair of engine sub-bases arranged longitudinally of said structure, generator supports on said member and sills in line with said sub-bases, each of said generator supports and sub-base portions being located equal distances on opposite sides of the transverse and longitudinal center lines of said structure.

44. In a railway vehicle underframe integral structure, center sill members, longitudinal sill members outside of said center sill members, engine sub-bases arranged longitudinally of said structure between said cen-

ter sill members and said outside sill members, said sub-bases being arranged symmetrically with the longitudinal and transverse center lines of said structure.

45. In a railway vehicle underframe integral structure, a box-shaped center sill member, longitudinal sill members on each side of said center sill member and engine sub-bases disposed longitudinally of the underframe on opposite sides of said center sill member and parallel to each other and formed integrally with said members.

46. In a railway vehicle underframe integral structure, end sills, side sills, and intermediate longitudinal and transverse members all having vertical webs, said webs having substantially horizontally aligned openings to receive piping extending along said underframe adjacent the inner sides of said side and end sills.

47. In a railway vehicle underframe integral structure comprising end sills, side sills, and intermediate longitudinal and transverse members having vertical webs, said webs having substantially horizontally aligned openings to accommodate water circulating pipes or train pipes extending along the inner periphery of the structure.

48. In a railway vehicle, an underframe integral structure having an end sill and a side sill and intermediate sills extending inwardly from said end sill and transverse members extending inwardly from said side sill, said intermediate sills and transverse members having vertical webs with substantially horizontally aligned openings adjacent the inner sides of said sills and members, and circulating or train pipes extending through said openings along said end sill and side sill.

49. In a railway vehicle underframe integral structure, a box shaped center sill and a box shaped bolster, the side walls of said sill and said bolster intersecting the central portion of said sill and bolster and said central portion between said walls being open top and bottom so as to form an air conduit.

50. In a railway vehicle underframe integral structure, a side sill having its intermediate portion on a higher level than its end portions, and a continuous horizontal pad on the outside of said sill for mounting side sheets, the intermediate portion of said pad being spaced from the top of said sill and the end portions of said pad being located on the upper portions of said sill end portions.

51. In a railway vehicle underframe including a side sill having its intermediate portion on a higher level than its end portions, pads on top of said sill along its outer edge, and means secured to said pads on said end portions for mounting side sheets, and vertically disposed means secured to said

pads on said intermediate portion for bracing the side sheets.

52. In a locomotive underframe integral structure, engine supporting elements including spaced longitudinal sill members having substantially vertical webs, and substantially horizontal members connecting said webs and forming therewith a box-like engine sub-base below said elements.

53. A railway vehicle underframe comprising an engine crank case and a liquid storage tank exterior of said crank case.

54. A railway vehicle underframe casting forming an engine sub-base structure and a fuel storage tank closed off from said sub-base structure.

55. A railway vehicle underframe including elements adapted to mount a cab and having an engine sub-base and a fuel storage tank formed as parts thereof, said tank being located below said elements.

56. In a railway vehicle, an underframe integral structure including a center sill and a bolster provided with a center plate, a blower housing mounted on said bolster over said centerplate, and an air conduit extending from said housing downwardly through said structure and said center-plate.

57. In a railway vehicle, an underframe integral structure including a box-shape center sill and a box-shape bolster having a center plate, a blower housing on said bolster over said center-plate, and an air conduit extending from said housing downwardly through said structure, the walls of said center sill and bolster forming walls of said conduit.

58. In a railway vehicle underframe, a longitudinal center sill, and a fluid chamber located outside of said sill and integral therewith with a portion of said sill forming a part of the wall of said chamber.

59. In a railway vehicle underframe, a bolster, and a reservoir member forming a part of the underframe structure with its end formed by a bolster wall.

60. A railway vehicle underframe comprising an integral device including center sill structure, a substantially horizontal web extending on opposite sides of said center sill structure, and upright members co-operating with said web and center sill structure to form separate reservoirs located on opposite sides of said center sill structure.

61. In a railway vehicle underframe, a plurality of reservoirs arranged side by side and extending longitudinally of the underframe with their adjacent walls constituting sill-like members of the underframe.

62. A railway-vehicle frame comprising a unitary casting constituting an under-bed for a prime mover, integral fuel tanks, a platform and a bumper, means on the casting for supporting a car body and means for mounting the frame on a supporting truck.

63. An under-bed for a heat engine and an electric generator that comprises an integral casting disposed to support the engine and generator in proper alignment, said casting being provided with integral fuel and water tanks.

64. An under-bed for a heat engine and an electric generator that comprises an integral casting disposed to support the engine and generator in proper alignment, said casting being provided with integral fuel and water tanks, means for supporting a car body on the casting and means for mounting the casting on a railway-vehicle truck.

65. A unitary railway-vehicle structural member comprising a frame, an engine crank case and a plurality of tanks formed integrally with the frame.

66. A railway-vehicle frame comprising a unitary casting constituting an under-bed for a prime mover, tanks associated with the prime mover, means on the casting for supporting a car body, a running gear for supporting the frame and motors for propelling the vehicle, the tanks for said prime mover being formed integrally with the unitary casting.

In testimony whereof I hereunto affix my signature this 31st day of Jan., 1929.

WILLIAM M. SHEEHAN.
